FOOT MASSAGER

Thomas Kellogg, Mamaroneck, N.Y., assignor, by mesne assignments, to The Songrand Corp., Kansas City, Mo., a corporation of Missouri

Filed Aug. 12, 1963, Ser. No. 76,185

Term of patent 14 years

(Cl. D83—1)

The undisclosed right side of the foot massager shown in FIG. 4 is substantially the same in appearance as the side shown.

I claim:

The ornamental design for a foot massager, as shown and described.
